UNITED STATES PATENT OFFICE.

CHARLES W. SVENSON, OF NEW BRITAIN, CONNECTICUT, ASSIGNOR TO CORBIN SCREW CORPORATION, OF NEW BRITAIN, CONNECTICUT, A CORPORATION OF CONNECTICUT.

ELECTRICAL CONNECTION.

No. 826,287.

Specification of Letters Patent.

Patented July 17, 1906.

Application filed September 1, 1904. Serial No. 222,932.

To all whom it may concern:

Be it known that I, CHARLES W. SVENSON, a citizen of the United States, residing at New Britain, in the county of Hartford, State of Connecticut, have invented certain new and useful Improvements in Electrical Connections, of which the following is a full, clear, and exact description.

My invention relates to improvements in electrical connections which are particularly useful for spark-plugs for internal-combustion engines and the like, although, of course, the invention is not confined to this use.

The main object is to provide a simple and effective connection, the construction of the same being such as to enable the user to adjust the cable at any desired angle relatively to the part to which it is attached without impairing the efficiency of said connection.

In the drawings I have shown my invention as applied to a spark-plug.

Figure 1 is a side elevation. Fig. 2 is a side elevation taken in a plane at right angles to that of Fig. 1. Fig. 3 is a plan view.

Fig. 4 is an elevation of a detached detail.

1 conventionally represents a portion of a spark-plug.

2 represents one of the electric terminals. Secured to this terminal in any convenient manner—for example, by means of a nut 3—is a metallic spring-clip furnishing side arms 4 4, which are so arranged as to yieldingly press toward each other and so as to grip with sufficient force any member that may be placed between them. In a suitable yielding portion of said side arms 4 4 perforations are formed to receive and securely hold and support a ball-like head 5 of a terminal member arranged to be secured to an electric cable 6 in any desired manner. The sides 4 4 preferably converge at an intermediate point to form a contracted throat or passage. The perforations are oppositely arranged in the contracted portion of the clip, and the edges of these perforations each afford a secure seat for the ball-like head 5. These seats are preferably circular in outline and by bearing against opposite sides of the ball-like head 5

hold the same against longitudinal or lateral displacement, but permit rotary and oscillating movement without interfering with the electrical connection.

As indicated in Figs. 1 and 2 by dotted lines, the head 5 may turn so that the cable may lead to the retaining-clip in a direct line 55 or at any angle thereto. The relatively extensive area of the seats for the head 5 insures a most satisfactory electrical connection, and any rolling or oscillating of the head 5 in said seats in said side arms 4 4 will keep 60 the contacting surfaces bright.

By the foregoing arrangement the connection is equally effective irrespective of the particular angle of the cable relatively to the clip or plug.

In the drawings I have shown the preferable construction of the clip, in which the ends of the side arms are free; but obviously this may be modified or its angle relatively to the spark-plug may be varied without departing from the spirit and scope of my invention.

By the term "perforation" I mean, of course, to include as an equivalent having some of the advantages a deep recess that 75 will afford a seat for the ball-like head which will resist longitudinal or lateral movement thereof, but will permit rotary or oscillating movement.

What I claim is—

An electrical connection device, comprising a base, a threaded terminal carried thereby, a clip, a nut operable on said terminal for securing said clip to said base, said clip having yielding side arms the ends of which approach each other and are provided with recesses, and a flexible conducting-wire member having a spherical tip adapted to be seated in said recesses.

Signed at New Britain, Connecticut, this 25th day of August, 1904.

CHARLES W. SVENSON.
